TELEPHONE DIRECTORY DEVICE

Alwin John Stahel II, New Brighton, Minn., assignor to
The Holes-Webay Co., St. Cloud, Minn.

Filed Aug. 14, 1972, Ser. No. 280,154

Term of patent 14 years

Int. Cl. D14—03

U.S. Cl. D26—14 A

FIG. 1 is a perspective view showing my ornamental telephone directory device;

FIG. 2 is a side elevational view thereof, the other side thereof being identical;

FIG. 3 is a top plan view thereof;

FIG. 4 is a front elevational view thereof;

FIG. 5 is a rear elevational view thereof; and

FIG. 6 is a bottom plan view thereof.

I claim:

The ornamental design for a telephone directory device, as shown.
